FRITZ FINCKH, OF ESSEN, GERMANY, ASSIGNOR TO FRIED. KRUPP AKTIENGESELLSCHAFT, OF ESSEN-ON-THE-RUHR, GERMANY.

GUN WITH RAILWAY GUN-CARRIAGE.

1,360,512.

Specification of Letters Patent. Patented Nov. 30, 1920.

Application filed September 4, 1920. Serial No. 408,377.

To all whom it may concern:

Be it known that I, FRITZ FINCKH, residing at Essen, Germany, a citizen of the German Republic, have invented a certain new and useful Improvement in Gun with Railway Gun-Carriage, of which the following is a specification.

This invention relates to guns with railway gun carriages and consists in an arrangement for the taking of the traverse.

The invention will be described with reference to the accompanying drawings in which—

Figure 1 is a side elevation, partly in section, a constructional example of the gun and

Fig. 2 is the corresponding plan view.

Figs. 3 and 4 are views corresponding to Figs. 1 and 2 of a second construction.

20 In addition—

Fig. 5 is a section on the line 5—5 of Figs. 1 and 3 looking from the left and

Fig. 6 is a section on the line 6—6 of Fig. 3 looking from the left.

25 The arrangement shown in Figs. 1, 2 and 5 will be described first.

The gun has a railway gun carriage, the frame A of which is carried at its front end on an intermediate support C which is carried on two bogies B B¹ and at its rear end on a bogie B². The pivot pin a¹ mounted on the intermediate carrier C and the pivot pins c¹, c², a² mounted on the bogies B, B¹, B² are constructed in the form of knuckle pins. The knuckle pin a¹ is rigidly connected to the frame A of the gun carriage and rests in a pan d¹ of a slide D which is movable at right angles to the longitudinal direction of the carrier C (see Figs. 1 and 5).

40 The slide D which is guided on ribs c³ (see Figs. 1 and 2) on the carrier C is moved by means of a screw spindle E which is mounted to rotate but not move longitudinally on the carrier C and engages in a female screw 45 thread on the slide (see particularly Fig. 5). The ends of the screw spindle E which project laterally over the sides of the carrier C each carry a hand wheel e¹. On the frame A of the gun carriage there is mounted by means of horizontal trunnions f² the cradle F¹ which carries the gun barrel F.

The rough traverse is imparted to the gun barrel in the well known way e. g. by running the gun along the rails. To obtain the 55 fine traverse the slide D is moved laterally

and relatively to the carrier C and the bogies B B¹ by rotating the spindle E. This movement is transmitted by the knuckle pin a¹ to the front end of the frame A of the gun carriage which is at the same time rocked 60 about the axis of rotation (a²) of the rear bogie B² (see Fig. 2). As, when the frame A of the gun carriage is trained around its front end, it moves over the arc of a circle and the slide D makes a straight line movement, the knuckle pin rotates in the pan d¹ of the slide D and the relative distance between the front bogies and the rear bogies is altered. The bogies are thereby moved 65 along the rails for a slight distance relatively to each other.

In the construction shown in Figs. 3, 4 and 6 the rear end of the frame A of the gun carriage is also movable laterally. For this purpose a screw spindle G, which is 70 mounted on the frame to rotate but not move longitudinally, and which is provided with hand wheels g¹, engages with a nut h². This nut and the pivot pin h¹ mounted in a pan b³ on the bogie B² are carried on a plate H, 75 on which the frame A is supported and slides when motion is imparted to it by the rotation of the screw spindle G.

To obtain the traverse the ends of the frame A of the gun carriage are moved in 80 opposite directions by suitably rotating the spindles E and G; the pivot pins a¹, h¹ also rotating in their bearing pans d¹, b³. By the simultaneous lateral movement of both 85 ends of the frame A a comparatively large 90 training angle is obtained.

Claims.

1. A railway gun carriage which comprises bogies, a frame and a gun carried by said frame, means for pivotally mounting 95 said frame at each end thereof on the bogies and means for traversing the frame relatively to the bogies.

2. A railway gun carriage which comprises two sets of bogies, a frame and a gun carried by said frame, means for pivotally supporting each end of the frame on one set of bogies and means whereby an end of the frame may be traversed, the pivot point of the frame on the other set of bogies there- 100 upon acting as a training axis.

3. A device of the class described, comprising a railway gun carriage, a frame supported thereon, a gun carried by said frame and means for laterally and independently 110

moving both ends of said frame, for training said gun, substantially as described.

4. A device of the class described comprising a railway gun carriage, a frame mounted thereon, a gun supported by said frame, and means for traversing one end of said frame which comprises a pivot pin, a slide and means for laterally moving said slide, as and for the purpose set forth.

10 5. A device of the class described comprising a railway gun carriage, a frame mounted thereon, a gun carried by said frame, said frame being capable of laterally

adjustment relative to the gun carriage and means for moving the front and rear ends of 15 said frame laterally, one of which means consists of a pivot pin, a plate carrying said pivot pin and a screw spindle operatively connected to said plate, substantially as described.

20 The foregoing specification signed at Essen, Germany, this 18th day of May, 1920.

FRITZ FINCKH.
